UNITED STATES PATENT OFFICE.

MORRIS P. HOLMES, OF CLAREMONT, NEW HAMPSHIRE, ASSIGNOR TO SULLIVAN MACHINERY COMPANY, A CORPORATION OF MASSACHUSETTS.

CUTTER CHAIN.

Application filed February 28, 1919, Serial No. 279,865. Renewed September 29, 1923.

To all whom it may concern:

Be it known that I, MORRIS P. HOLMES, a citizen of the United States, residing at Claremont, in the county of Sullivan and State of New Hampshire, have invented certain new and useful Improvements in Cutter Chains, of which the following is a full, clear, and exact specification.

My invention relates to cutter chains.

It has for its object to provide an improved cutter chain, and, though not limited thereto, more especially an improved cutter chain adapted to use on a mining machine. A further object of my invention is to provide an improved and simplified cutter chain comprising a minimum number of different cutter links of improved construction. A still further object of my invention is to provide an improved cutter link and an improved series of the same whereby the arrangement of the cutter bits and the positions of the same upon the cutter chain may be varied within wide limits. These and other objects and advantages of my improved construction will, however, herein-after more fully appear.

In the accompanying drawings, I have shown for purposes of illustration one embodiment which my invention may assume in practice.

In these drawings,—

Fig. 1 is a side elevation, partially in section, of a section of chain constructed in accordance with my improvement.

Fig. 2 is a plan view of the same.

Fig. 3 is a sectional view taken on line 3—3 of Fig. 1.

Fig. 4 is a sectional view taken on line 4—4 of Fig. 1.

Fig. 5 is a sectional view taken on line 5—5 of Fig. 1.

Fig. 6 is a diagrammatic view of the arrangement of two cooperating unit chain sections.

In this illustrative construction I have shown a cutter chain comprising cutter links 1 and connecting links 2, the same herein being pivotally connected at 3 and arranged in alternative relation, although obviously the sequence of the links may be varied as desired.

In my improved construction, it will be observed that the cutter links 1 are of a substantial character, the same preferably being

of integral construction and made of cast steel or a suitable forging. As illustrated, each of these links has on each end of the same and near its base, a single longitudinally extending, centrally located extension or ear 4 having flat sides and a rounded end, and each of these extensions 4 is provided with a transverse bore 5 adapted to receive the pivot pin 3 and thereby operatively connect the two elements of the link 2 to the extension. Here it will also be observed that these extensions 4 are symmetrical so that each link 1 may be turned end for end when desired. It will also be observed that each link 1 is provided with a lateral extension or boss 6 on its body, herein having a plurality of transverse inclined slots 7 and 8 therein disposed in intersecting planes and preferably spaced longitudinally of the portion 6. As shown, these slots 7 and 8 carry therein cutter bits, in the case of the left hand link (Fig. 1) indicated, respectively, at 9 and 10, the bits being respectively clamped in their slots by means of set screws 11 and 12. It will also be observed that the inward movement of each of the bits in its slot is limited by means of a pin 13 disposed transversely across the inner ends of the slots, means thereby being provided to prevent straight bits or picks from sliding through the slots before they can be clamped in position therein.

Referring now more particularly to the left hand cutter link shown in Figs. 1 and 3, it will be observed that the slots 7 and 8 therein are disposed substantially at right angles to one another, and that the boss 6 is provided with two longitudinally spaced lateral extensions or bosses 14 and 15, of which the extension 14 is higher than the extension 15. It will also be observed that the bits 9 and 10 extend centrally through these extensions 14 and 15, respectively, and are so disposed that the angle between the bit 9 and the longitudinal center line of the link (dotted in Fig. 3) is slightly less than the angle between the bit 10 and this line. Referring now to the second or center cutter bit shown in Fig. 1, and also shown in Fig. 4, it will be observed that the boss 6 thereof is also provided with two longitudinally spaced lateral extensions or bosses 16 and 17. These bosses 16 and 17, however, do not extend as far laterally as the extensions

14 and 15 on the first link, and carry in their slots 7 and 8, respectively, angularly disposed cutter bits 18 and 19, of which the angle between the bit 18 and the longitudinal center line of the link (dotted in Fig. 4) is smaller than the angle between the bit 19 and that line. Here it will also be noted that the angle between the bit 19 and that line is less than the angle between the bit 9 and that line. Referring now to the right hand link shown in Fig. 1 and also shown in Fig. 5, it will here be observed that the boss 6 is provided with only slightly laterally disposed, longitudinally spaced extensions 15 or bosses 20 and 21, and that located substantially centrally in these members 20 and 21 are cutter bits 22 and 23, of which it will be noted that the bit 22 is disposed substantially in the longitudinal center line of the link (dotted in Fig. 5), while the bit 23 is disposed at a slight angle with respect to that line but at an angle thereto less than the angle of the bit 18 to the line.

Summing up the different positions of the bits, it will be observed that the order of the same as their angle to the center line decreases, is as follows: 10, 9, 19, 18, 23, and 22. In other words, a unit section having the bits thereof arranged in six-positions is produced. This section of chain may obviously be extended to any desired length by simply adding thereto any number of connected series of cutter links such as described, the links of alternative sections, 35 however, being turned end for end and having their bits reversed. It will thus be observed that through the reversibility of the links 1 it is possible to produce with only three stock cutter links, a twelve-position 40 chain, wherein the bits on the links of the reversed series are so disposed that their paths lie adjacent the paths cut by the bits on the series in their other position. More particularly, it will be observed that this is 45 accomplished by simply turning the links end for end and reversing the direction of the bit points to get the other six positions. The reversible feature will be more readily seen by having reference to Fig. 6 wherein 50 it will be noted that bits of one sectional unit are disposed in lines A and B which, when extended, intersect. The remainder of the bits which would constitute the bits in the reversed sectional unit lie in lines A' and B' which, when extended, also intersect. It is to be noted that the angles X and X' of the intersecting lines A—B and A'—B', respectively, are substantially 55 equal. It will also be observed that with 60 my improved construction it is possible not only thus to reverse the individual links, but to reverse a complete section of three links or a series of such sections comprising a chain, and that it is also possible to produce any desired one of a wide number of 65

variations by reversing any particular link. It will also be noted that since the wear on a cutter link usually comes at one end of the same, i. e. upon one of the ears 4, through this reversibility of my improved links it is 70 possible to double the life thereof, the link when reversed presenting a new and unworn member 4. Obviously, while the advantages described above may be obtained in connection with links carrying a plurality 75 of bits, further wide variations in the arrangement of the bits may be effected by utilizing only one bit in each link or in certain links and adjusting this bit in either of the four bit positions presentable by each 80 link.

It will be observed that each bit as shown in Fig. 2 will cut a path the width of a single bit, which path alternates with an uncut path. For instance, the bits 22, 23 are transversely spaced a distance equal to the width of a bit. The bits 19 and 23 are also transversely spaced a distance equal to the width of one bit. This arrangement is also true of bits 19 and 10, 9 and 18, and 18 and 22.

In connection with my improvement, attention is particularly directed to the fact that the links are of an exceedingly rugged construction, the same being capable of being cast or forged in one piece so that they may well withstand hard service. It is also particularly to be noted that through the use of my improvement it is possible, while retaining a link of this desired character, to obtain an extremely wide range of bit positions adapting the chain to any known service condition encountered in soft or hard cutting and to insert kerfs of widely varying widths adapted to the conditions and cutting encountered. It will also be especially observed that through my improvement it is possible to equip a complete chain having all of these various adjustments with only three types of cutterlinks, 105 thereby materially simplifying the manufacturing problems and also eliminating any necessity for the user to keep in stock for repairs any more extensive stock than a supply of each of the three links, thereby 110 materially reducing his investment in repairs and the difficulties and delays ordinarily attendant upon making the same. These and other advantages of my improved construction will, however, be clearly 115 apparent to those skilled in the art.

While I have in this application specifically described one embodiment which my invention may assume in practice, it is to be understood that this form is shown for illustrative purposes only and that the invention may be modified and embodied in various other forms without departing from its spirit or the scope of the appended claims.

What I claim as new and desire to secure by Letters Patent is:

1. A cutter chain comprising a plurality of links, and a plurality of cutter bits forming a set carried by each of said links, said bits in each set being disposed at unequal angles to the median line of said link and the angle between the bits of one set being different from the angle between bits of another set. 70
2. A cutter chain comprising a plurality of links, a plurality of cutter bits forming a set carried by each of said links, said bits in each set being disposed at unequal angles to the median line of said link and the angle between the bits of one set being different from the angle between bits of another set, said plurality of bits and links forming a unit, and sets of bits forming a second unit arranged with respect to each other substantially identical to the bits of the first unit, and so arranged that the bits on the opposite sides of the median line of corresponding sets in the units make the same angle with respect to the median line. 80
3. A cutter chain comprising a plurality of links, and a plurality of cutter bits forming a set carried by each of said links, said bits in each set being disposed at unequal angles to the median line of said link and the angle between the bits of one set being different from the angle between bits of another set, one set of bits being so arranged that they cut paths that are disposed on the outside of the paths cut by the bits of another set. 95
4. A cutter chain comprising a plurality of links, and a plurality of cutter bits forming a set carried by each of said links, said bits in each set being disposed at unequal angles to the median line of said link and the angle between the bits of one set being different from the angle between the bits of another set, the bits of said sets being so disposed as to cut paths that alternate with uncut paths. 105
5. A cutter chain comprising a plurality of links, a plurality of cutter bits forming a set carried by each of said links, said bits in each set being disposed at unequal angles to the median line of said link and the angle between the bits of one set being different from the angle between the bits of another set, the bits of said sets being so disposed as to cut paths that alternate with uncut paths, and additional bits adapted to cut said uncut paths. 115
6. A cutter chain comprising a plurality of links, a plurality of cutter bits forming a set carried by each of said links, said bits in each set being disposed at unequal angles to the median line of said link and the angle between the bits of one set being different from the angle between the bits of another set, said sets of bits forming a unit, the bits of said unit being so disposed as to cut paths that alternate with uncut paths, and a second set of bits forming another unit substantially identical to the first unit, the bits in said second unit being disposed to follow the first unit to cut the uncut paths. 125
7. A cutter chain comprising a plurality of links and bits carried thereby, some of said bits being so disposed that they lie substantially in extended lines that intersect, while the remainder of said bits likewise lie in extended lines that intersect and both sets of intersecting lines have substantially equal angles, said bits being so disposed that substantially only one line passes through each bit and so that the bits disposed in one set cooperate with the bits of the other set to make a single complete cut within the limits of the outermost bits in said lines. 135
8. A cutter chain comprising a plurality of links and bits carried thereby, some of said bits being so disposed that they lie substantially in extended lines that intersect while the remainder of said bits likewise lie in extended lines that intersect and both sets of intersecting lines have substantially equal angles, said bits being so disposed that substantially only one line passes through each bit and so that the bits disposed in one set of lines travel in paths that are alternately arranged with respect to the paths traveled by the remaining bits. 145
9. A cutter chain comprising a plurality of links and bits carried thereby, some of said bits being so disposed that they lie substantially in extended lines that intersect while the remainder of said bits likewise lie in extended lines that intersect and both sets of intersecting lines have substantially equal angles, the bits disposed in one set of lines traveling in paths that are alternately arranged with respect to the paths traveled by the remaining bits and the arrangement of said bits being such that the paths cut by the bits have communication substantially with each other. 155
10. A cutter chain comprising a plurality of links and bits carried thereby, some of said bits being so disposed that they lie substantially in extended lines that intersect while the remainder of said bits likewise lie in extended lines that intersect and both sets of intersecting lines have substantially equal angles, and that each of the bits disposed in one set of lines travels in a path that is alternately arranged with respect to the paths traveled by the remaining bits. 165
11. A cutter chain comprising a plurality of links, said links being divided into sets and each set including a plurality of links carrying bits wherein each bit of the first set is adapted to cut a single path that alternates with uncut portions while the bits of the second set are adapted to cut paths in said uncut portions, and the bits of one set forming a unit, the bits of the second set being disposed to follow the first set to cut the uncut portions. 175

set having the same longitudinal and transverse arrangement with respect to each other as the bits in the other set.

12. A cutter chain comprising a plurality of links some of which are substantially identical in construction, said links being divided into sets and each set including a plurality of links carrying bits wherein each bit of the first set is adapted to cut a single path 10 that alternates with uncut portions, and the bits of the second set being adapted to cut paths in said uncut portions.

13. A cutter chain comprising a plurality of links, said links being divided into sets 15 and each set including a plurality of links carrying bits wherein each bit of the first set is adapted to cut a single path that alternates with uncut portions while the bits of the second set cut paths in said uncut portions 20 and the bits of each set being disposed in substantially identical arrangements that are symmetrical.

14. A cutter chain comprising a plurality of series of bits, the bits of one of said series 25 all being disposed within a wedge-shaped formation while the remaining bits are disposed to the rear of the foremost bit in said formation, and each bit of one series being adapted to cut a path that alternates with 30 uncut paths while the remaining bits are so disposed that they travel in said uncut portions.

15. A cutter chain comprising a plurality of identical series of bits wherein the arrangement of the bits with respect to each other in one series is substantially identical 35 to the arrangement of the bits in the other series while the bits of each series are disposed within wedge-shaped formations 40 which have their longitudinal axes offset relative to each other, so that the bits of one series are thereby so disposed that they cut paths that alternate with uncut paths, and the bits of the second series being so 45 disposed that they cut in said uncut paths.

16. A cutter chain for use on a mining machine of the cutter bar type comprising a plurality of series of links each having a plurality of bits arranged at different angles 50 and on opposite sides of the central plane of said cutter bar, the angles of the bits on one link of a series being greater than those of the bits on an adjacent link and the links in adjacent series being reversed, whereby 55 the bits of each series cut in the spaces between the paths of the bits in the other series.

17. A cutter chain intended for orbital

movement comprising a plurality of series of links each of which links is provided with 60 a plurality of bits, the bits of each link being arranged at different angles to the plane of said orbit, and the maximum angle of either bit on one link being less than that of either bit on one of the adjacent links and 65 the links in adjacent series being reversed, whereby the bits of each series cut in the spaces between the paths of the bits in the other series.

18. A cutter chain comprising a plurality of series of links each of said links being provided with a plurality of cutter bits disposed at different angles to the median line thereof, the minimum angle of either bit on one link being greater than the maximum angle of either bit on one of the adjacent links and the maximum angle of either of the bits of said first mentioned link being less than the minimum angle of either bit on the other link adjacent it and the links in adjacent 80 series being reversed, whereby the bits of each series cut in the spaces adjacent the paths of the bits in the other series.

19. In a cutter chain, a series of cutter links each provided with a plurality of cutter bits reversibly disposed at different angles to the median line thereof, said links being reversible and the angles of said bits such that the paths cut by the bits of each of said links upon reversal of said links will 90 overlap the paths cut by said bits prior to reversal.

20. A cutter chain comprising a series of dissimilar cutting links on each of which a pair of bits are carried, the links and bits 95 being reversible, the angle between the bits on each link being different from the angle between the bits on the other dissimilar links and the bits on each link making different angles with the median longitudinal 100 plane of the link, said parts being so arranged that the path cut by each of the bits of any given link after the reversal of the link and bits will adjoin the path cut by the other bit of said link prior to the reversal.

21. A cutter chain composed of a series of reversible cutter links each having a plurality of bits disposed therein at different angles to the median line of said links, said 110 bits being adapted, upon reversal of said parts to cut adjacent the paths cut by said bits before reversal of said links.

In testimony whereof I affix my signature.

MORRIS P. HOLMES.
